(57) **CLAIM**

The ornamental design for a cable end connector, as shown and described.

DESCRIPTION

FIG. 1 is a front, top and right side perspective view of a cable end connector showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

The cable shown in phantom lines is for illustrative purposes only and forms no part of the claimed invention.
